UNITED STATES PATENT OFFICE.

ELWOOD B. AYRES, OF MELROSE PARK, AND CHARLES S. MORRISON, OF ELKINS PARK, PENNSYLVANIA, ASSIGNEES TO PROCTOR & SCHWARTZ, INCORPORATED, OF PHILADELPHIA, PENNSYLVANIA, A CORPORATION OF PENNSYLVANIA.

DRIER.

Application filed November 24, 1923. Serial No. 676,788.

Our invention relates to certain improvements in apparatus for drying leather.

One object of the invention is to construct the apparatus so that the carriers, on which the leather is stretched, are located in chambers on each side of a heating and circulating chamber.

A further object of the invention is to improve the construction of the frames on which the carriers are mounted.

In the accompanying drawings:

Fig. 1 is a transverse sectional view on the line 1—1, Fig. 3;

Fig. 2 is a plan view of the drier with the outside frames removed;

Fig. 3 is a side elevation of one-half of the drier;

Fig. 4 is a longitudinal sectional view on the line 4—4, Fig. 2, of one half of the drier, showing the air circulating fans and the heating means;

Fig. 5 is a view of one of the frames with a carrier mounted thereon;

Fig. 6 is an end view of one of the frames;

Fig. 7 is a sectional plan view of a series of frames taken on the line 7—7, Fig. 5;

Fig. 8 is a sectional perspective view of the lower portion of a frame and carrier;

Fig. 9 is an enlarged sectional view on the line 9—9, Fig. 1, showing a series of frames and carriers in a drying chamber;

Fig. 10 is an enlarged sectional plan view of part of Fig. 7;

Fig. 11 is an enlarged vertical sectional view on the line 11—11, Fig. 5;

Figs. 12, 13 and 14 are detail views of one of the trunnions and bearing for the carrier;

Figs. 15, 16 and 17 are detail views of one of the catches for holding the carrier in the frame;

Fig. 18 is a detached perspective view, illustrating the bumper bar;

Fig. 19 is a view of the notched rail for holding the frames when they are withdrawn from the drier; and

Fig. 20 is a perspective view of a modification.

Referring to the drawings, 1 is the casing of a drier, which may be of any length desired. This casing has side walls 2 that extend from the roof of the drier to the upper portion of the movable frames 3. 4,

4 are vertical partitions that have openings at top and bottom for the free circulation of heated air. These partitions 4, 4 separate the central heating and circulating chamber *a* from the two drying chambers *b*, *b*. The outer sides of these chambers *b* are closed by the flanges 24 on the carriers 23, which are mounted in the frames 3, when the frames are located in the drying chambers, and by the inner end members 6 of the frames 3, when they are withdrawn from the drying chambers, as shown in Fig. 1.

In the central chamber is a series of circulating fans 7, which are mounted on vertical shafts 8 that are driven from a longitudinal shaft 9 by suitable gearing. The longitudinal shaft 9, and the bearings for the shaft 8, are located in a tunnel *c*, which is formed by inclined side plates 10 so as to protect them from the heated air in circulation.

Between the partitions 4, 4 and the side plates 10, 10 are heating pipes 11. These pipes are preferably located below the series of fans 7.

Projecting from each side of the drier are overhead rails 12. The outer ends of the rails are supported by diagonal braces 13 and frames 14, suspended from the ceiling of the room. The inner ends of the rails are secured to the side walls 2, as shown in Fig. 1.

Located at the bottom of each drying chamber are grooved rails 15, which align with the overhead rails 12. The frames 3 are made as shown in Figs. 5 and 6. Each frame consists of an outer end member 5, 90 an inner end member 6, and an overhead connecting member 16. The overhead member is reinforced at the corners of the frame by braces 17, Fig. 5. The outer end member 5 is extended and has, at its upper end, a grooved wheel 18, which is mounted on one of the overhead rails 12. At the lower portion of each inner end member 6 of the frame is a bracket 20, on which are mounted rollers 19 that are arranged to travel in the grooved rails 15.

On the two end members of the frame 3 are sockets 21 for trunnions 22, attached to the carrier 23, made in the form of a rectangular frame having braces 25 at the corners. On each carrier is secured per-

forated metal 26, in the present instance, to which the clamps, which are attached to the leather, are secured.

The clamps are similar to those shown in the patent granted to Walter M. Schwartz and Elwood B. Ayres, on May 8, 1923, No. 1,454,694.

The grooved rails 15 are spaced a given distance apart to allow sufficient space between the carriers for the free circulation of air past the leather, which is secured to the carriers. The grooved rails are also of such a height as to engage the lower portions of the carriers, as well as the rollers of the frame, thereby holding the carriers in a vertical position, and guiding the frame. When the frames are withdrawn, the carriers are free to be turned on their trunnions.

By the construction hereinbefore described, the sides of the drying chambers are open, but they are closed by the flanges of the carriers when the frames are pushed into the drier, and are closed by the flanges on the inner member of the frames, when the frames are withdrawn.

The spaces on each side of the frames above the carrier are closed by the depending portions 27 of the bumper bars 28, against which the members 5 of the frames strike, when the frames are pushed into the drier. When the frames are withdrawn from the drier, the lower portions of the members 5 enter notches 29 in a plate 30 that is secured to the floor, in the present instance.

The trunnions 22 of the carriers have V notches 31, as shown in Fig. 4. On the socket 21, which is secured to the frame, is a V-shaped pin 32 that is arranged to enter one of the notches in the trunnions. The function of the pin is to hold a carrier from swinging freely when in a horizontal position. In order to lock the carriers to the frames, latches 33 are provided. These latches slide on a bracket 34 on the overhead connecting member 16.

One arm of each latch is longer than the other arm, as shown in Figs. 15 and 17 so that, on raising the latches, a carrier can be turned on its pivot under the long arms of the latches to a horizontal position, and, after a skin is secured in position, the carrier can be turned completely over, passing the latches, and another skin can be secured to the opposite side of the carrier, after which the carrier is returned to its vertical position and comes in contact with the long arms of the latches and is engaged by them, so that it is held firmly to the frame.

Fig. 20 illustrates a modification of the means for preventing the frames swinging laterally when they are withdrawn from the drier.

The overhead rails 12^a are preferably elevated above that shown in Fig. 1, and two

angle iron guides 30^a are located under each rail so that the frames 3 slide between them. The guide rails are so located that the carriers will clear them when turned on their pivots. The rails take the place of the notched floor plate 30, and guide the frames, giving them a certain amount of stiffness. The overhead rails 12^a are T-shaped in this instance.

We claim:

1. The combination in a drier, of a casing having a drying chamber, one side of the chamber being entirely open; means for circulating heated air in the chamber; and a series of movable material-supporting frames, each frame having a vertical closing member at each end, each closing member having an inturned vertical flange at each edge, the closing members of one frame abutting those of adjoining frames, when said frames are in either of their extreme positions.

2. The combination in a drier, of a casing; longitudinal partitions therein separating the casing into a central heating and circulating chamber and side drying chambers, said drying chambers being open at the outer sides; and a series of material-carrying frames each frame having vertical closing members, the closing members of one frame abutting those of adjoining frames when the frames are located in the chamber.

3. The combination in a drier, of a casing enclosing a drying chamber; means for circulating heated air in said chamber; a series of overhead outside rails and a series of inside guide rails at the bottom of the chamber; frames arranged to travel on said rails; and pivoted carriers on the frames, held vertically by the lower guide rails when the frames are in the drier.

4. The combination in a drier, of a casing enclosing a drying chamber, which is open at one side; means for circulating heated air in said chamber; a series of overhead outside rails at the open side of the drying chamber; a series of inside guide rails at the bottom of the chamber; a series of frames, each frame having a wheel at the outer end adapted to travel on an outside overhead rail and having a roller at the lower end at the inner side adapted to travel in an inside guide rail; a carrier pivoted to each frame and arranged so that its lower end travels in the guide rail; a closing flange on each carrier arranged with abutting flanges of adjoining carrier to close the open side of the drying chamber when the frames are in the drier; and a flange on each frame arranged to close the open side of the drying chamber when the frames are withdrawn.

5. The combination in a drier, of a drying chamber; means for circulating heated air therein; a series of frames arranged to be

- moved into the drier; rails for supporting the frames; carriers pivotally mounted on the frames; and means, on the frames, for holding the carriers in a vertical position.
6. The combination of a drier having a drying chamber; frames arranged to be moved into and out of the drier; carriers pivotally mounted on the frames, the trunnions of each carrier having notches; sockets on the frames for the trunnions; and V-shaped projections on the sockets extending into the notches in the trunnions when the carriers are in a horizontal position.
7. The combination of a drier having a drying chamber; means for circulating air in said chamber, one side of the chamber being open; a series of frames arranged to slide into and out of the drying chamber; and carriers, pivotally mounted on the frames, having portions that abut one another and form a closure for the open side of the drying chamber.
8. The combination of a drier having a drying chamber with an open side; a series of outside, overhead rails arranged side by side; a series of frames arranged to slide into and out of the drying chamber and carried by said rails; carriers on the frames; means, on the carriers, for closing the drying chamber; and an abutment bar located above the side opening of the drying chamber, said bar having spaced, depending portions extending between the frames.
9. The combination in a drier, of a frame arranged to be moved into and out of the drier; a carrier pivotally mounted on the frame; and a latch on the frame arranged to engage the carrier, said latch having two arms spanning the edge of the carrier, one arm being longer than the other and acting as a stop when the carrier is turned on its pivots.
10. The combination of a drier having a drying chamber; means for circulating air in the chamber, one side of the drying chamber being open; a series of overhead, outside rails; a series of grooved rails at the floor of the drying chamber; a series of frames, each frame having an outer, upper roller arranged to travel on an overhead rail, and having rollers located at the lower, inner end, which travel in a grooved rail; a carrier pivotally mounted on a frame; a latch for locking a carrier to a frame; means, at the trunnions of a carrier, for frictionally holding a carrier in a horizontal position; means for holding a frame laterally when withdrawn from the drier; and means for closing the open side of the drier when the frames are in position in the drying chamber, or are withdrawn therefrom.
11. The combination in a drier, of a casting having a drying chamber; means for circulating heated air in said chamber, one side of said chamber being entirely open for
- the reception of movable material-supporting carriers; a series of carriers arranged side by side and having vertical closing members at the front end so that when the carriers are within the drier the opening will be closed by the closing members; and means for supporting the carriers at their outer ends when withdrawn, said supporting means allowing the carriers to be turned from a vertical to a substantially horizontal position, to allow the dried material to be removed from the carriers and other material secured thereto.
12. The combination in a drier, of a casting having a drying chamber; means for circulating heated air in said chamber, one side of said chamber being entirely open for the reception of movable material-supporting carriers; a series of carriers arranged side by side and having vertical closing members at each end so that when the carriers are within the drier or drawn out to their full extent the opening will be closed by the closing members; and means for supporting the carriers at their outer ends when withdrawn, said supporting means allowing the carriers to be turned from a vertical to a substantially horizontal position, to allow the dried material to be removed from the carriers and other material secured thereto.
13. The combination in a drier, of a casting having a drying chamber; means for circulating heated air in said chamber, one side of said chamber being entirely open; a series of upper and lower guide rails within the chamber; a series of carriers arranged to be guided by the upper and lower guide rails, each carrier having a vertical closing member at each end, the closing member of one carrier abutting that of an adjoining carrier; and means on the outside of the drier for supporting each carrier, said supporting means being arranged so that the carrier can be turned from a vertical to a substantially horizontal position, to allow the dried material to be removed from the carrier and other material secured thereto.
14. The combination in a drier, of a casting having a drying chamber; means for circulating heated air in said chamber, one side of said chamber being entirely open; and a series of carriers vertically arranged side by side within the chamber, said carriers having vertical closing members at each end, the closing member of one carrier abutting that of an adjoining carrier, so that when a carrier is within the drying chamber or drawn out to its full extent the opening will be closed by the closing member, the closing members at the front of the drier having inturned flanges, and the closing members at the rear of the drier having out-turned flanges, said flanges being bent beyond the right angle so as to form a

tapered guide for the carriers when they are moved into and out of position.

15. The combination in a drier, of a casting having a drying chamber; means for circulating heated air in said chamber, one side of said chamber having an extended opening; and a series of carriers mounted in the opening, each carrier having a vertical closing member at the front end, the

closing member of one carrier abutting those of other carriers, said closing members having inturned flanges, the flanges being bent past the right angle so that the flanges of one carrier will act as beveled guides for the carrier between them. ¹⁰
